ARTHUR GAUDENZI, OF BADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

ELECTRIC POWER RECTIFIER CATHODE CONSTRUCTION

Application filed March 15, 1929, Serial No. 247,270, and in Germany March 15, 1928.

This invention relates to the improvements in the construction of metallic vapor rectifiers and, more particularly, to an improved cathode construction of the same.

The heating effect of the electric arc during the operation of metallic vapor rectifiers, especially when used in power installations and, therefore, in large sizes, produces excessive amounts of vapor thereby creating a vapor pressure which it is desirable to keep as low as possible for the purpose of preventing condensation of the metallic vapor on the anodes and on the walls of the rectifier chamber. Such condensation would result in the formation of a so-called cathode spot having a negative potential permitting a reverse flow of the current. The probability and the character of damage resulting from such backfires or reverse current are well known in the art. Various means have been proposed to diminish the mass of metallic vapor within the rectifier such as, cooling of the cathode, enclosing the anodes in separate chambers or supplying sleeves about the anodes, as well as many other means.

The excessive production of metallic vapor in electric current rectifiers is caused by movement of the arc over the surface of the cathode thereby uselessly heating the entire surface of the cathode. The conditions to be met in preventing the formation of excessive vapor are; fixation of the arc to prevent movement thereof over the entire surface of the cathode, and cooling of the body of the cathode below the vaporization point so that the same may act as a condensing surface for the vaporized metal.

It is, therefore, among the objects of the present invention to provide a cathode for electric current rectifiers which will prevent the formation of excessive amounts of vapor therein.

Another object of the present invention is to provide a cathode structure for metallic vapor rectifiers in which the arc will be fixed or will be permitted to move only very slowly over the cathode surface.

A further object of the invention is to provide cooling means for the cathodes of metallic vapor rectifiers which will maintain the

cathode body at a temperature lower than the vaporization point.

Objects and advantages, other than those above set forth, will be apparent from the description and the drawings, in which

Figure 1 is a partial vertical sectional view, 55 showing one embodiment of the invention;

Fig. 2 is a similar partial sectional view of a modified form of an embodiment of the invention, and

Fig. 3 is a plan view taken on line A—A, showing the structure of the arc fixing means.

Referring more particularly to the drawings by characters of reference, the reference numeral 5 indicates a portion of the bottom of a rectifier chamber and is formed, as is usual, in the shape of an inverted hollow truncated cone, which provides a circular aperture therethrough. The bottom may be made double walled to permit circulation of a cooling medium therethrough or may be made as a single wall when cooling thereof is not required.

A substantially cylindrical member 6 of quartz or other equally difficultly fusible, 75 electrical insulating material is connected with the bottom 5 and, with a bottom closure plate 7 forms a container or well, the purpose of which will appear hereinafter. The closure plate 7 is formed of copper or other material having a high coefficient of heat 80 conductivity and is cut out, from the upper surface downwardly, to receive a cathode plate 8. The cathode plate 8 is, preferably of good heat conducting material, formed as a complement to the cut out portion of closure 85 7 and is provided with perforations 10 connected by channels 11 cut into the under side of the plate.

The surface of plate 8 is covered or coated 90 with a protective film 12 of some highly infusible material, such as tungsten, which extends partially into the perforations 10. Such film may be applied to the plate by any well-known mechanical or electrolytic means.

An electrical and heat insulating packing 13, preferably of asbestos, is arranged within cylinder 6 and is held in position by a sheath 15 of chromium or other high melting point material not attacked by mercury. The 100

sheath 15 is inserted into a groove formed in plate 8 in contact with protective film 12 in such manner that it will be impossible for the electric arc to come into direct contact with plate 8. The inner surface of cylinder 6 may also be coated with chromium or tungsten to increase the protection thereof against the action of the arc. Sufficient mercury is placed within the receptacle formed by sheath 15, plate 8 and closure 7 to cover the protective film 12 on plate 8 to such depth that the same will be penetrated by the arc, during operation, in such manner that the arc will be fixed or attached to the film 12 and that the mercury meniscui in perforations 10 will always be in contact with film 12.

Any heating of the cathode structure is reduced to a low value by absorption of the heat in a cooling medium flowing into a water-jacket formed by a chamber 16 arranged below closure 7, through an inlet conduit 17 and escaping therefrom by way of an outlet conduit 18. The arc being fixed on film 12 vaporizes only that portion of the mercury immediately adjacent the point of attachment while the remainder of the cathode structure is cooled by conduction of heat through closure 7 to the cooling medium in water-jacket 16.

In a modified form of the invention, shown in Fig. 2, closure 17 itself is hollowed out to form a chamber for the circulation of the cooling medium. The chamber is closed by an imperforate cathode plate 20 which is formed with grooves or cup-like depressions 21. The plate 20 is covered with a protective sheath 22 conforming to the configuration thereof. In this instance, the mercury fills the depressions 21.

It will be apparent that the present invention provides a structure which will prevent excessive vaporization of mercury by diminishing the movement of the arc over the surface of the cathode and by cooling the cathode structure in such manner that conduction of heat, produced by the arc, to the entire cathode is avoided.

Although only two embodiments of the invention have been illustrated and described, it will be understood that various other embodiments are possible, and that various changes may be made without departing from the spirit of the invention or the scope of the claims.

The invention claimed is:

1. In a cathode structure of an electric-current rectifying device of the metallic vapor type having a bottom provided with an aperture therethrough, an electrical insulating cylinder connected with said bottom, a closure member of heat conducting material connected with said cylinder, a body of mercury retained within said insulating cylinder and said closure member, a heat conducting plate within the space enclosed by said cylinder

and said closure, exposed portions of said plate alternating with exposed surfaces of mercury, a sheath of difficultly fusible material for protecting said plate from direct contact with an electric arc, and means connected with said closure for cooling the same. 70

2. In a cathode structure of an electric current rectifying device of the metallic vapor type having a bottom provided with an aperture therethrough, an electrical insulating cylinder connected with said bottom, a closure member of heat conducting material connected with said cylinder, a body of mercury retained within said insulating cylinder and said closure member, means for protecting said cylinder from the action of an electric arc, means within the well formed by said cylinder and said closure for fixing the attachment of the electric arc, a sheathing for protecting said means from direct contact with the arc, exposed portions of said sheathing alternating with exposed portions of mercury, and means connected with said closure for cooling the same. 80 75

3. In a cathode structure of an electric current rectifying device of the metallic vapor type having a bottom provided with an aperture therethrough, an electrical insulating cylinder connected with said bottom, a closure member of heat conducting material connected with said cylinder, a heat conducting plate within the space enclosed by said cylinder and said closure, a sheathing of difficultly fusible material for protecting said plate from direct contact with an electric arc, a body of mercury forming a film partially covering said protective sheathing, exposed portions of said sheathing alternating with exposed portions of mercury, and means connected with said closure for cooling the same. 90 95 100

In testimony whereof I have hereunto subscribed my name this 2nd day of March, A. D. 1929.

ARTHUR GAUDENZI.
